BATTERY SUPPORTING MEANS FOR LOOMS

William H. Bahan, Greenville, S. C.; Edward F. Bahan, administrator of said William H. Bahan, deceased

Application March 13, 1948, Serial No. 14,696

3 Claims. (Cl. 139—249)

1

This invention relates to an improvement in battery looms and more especially to additionally supporting the battery of the loom and also for supporting the bobbin supporting means associated with the hopper of the battery loom, especially when the projection on the hopper for supporting the bobbin support is broken as often happens.

Also, there is a tendency at the present date to try to speed up the number of picks per minute in looms. As long as a loom is running around 150 picks per minute, the vibration is not so great, but when this loom is operated at from 170 or more picks per minute, there is excessive vibration in the loom and by my improved supporting means the amount of vibration and damage to the loom is greatly overcome.

Also, it often happens that the peripheral projection on the lower portion of the hopper stand of a loom which accommodates a pivot bolt for the bobbin support which supports a bobbin about to be transferred is broken away and thus the hopper stand is rendered useless and a new hopper stand has to be installed, but by my improved means, an additional support for the pivot bolt of the bobbin support can be provided and the old hopper which has been broken can be used without the necessity of discarding the same.

It is therefore an object of this invention to provide means secured to a rigid portion of the loom and also secured to the hopper of the battery in a battery loom for additionally supporting the battery hopper, and said supporting means can also, if desired, have a supporting means extending therefrom to a point where the bobbin support can be supported especially when the bobbin supporting portion of the hopper has been broken away.

Some of the objects of the invention having been stated, other objects will appear as the description proceeds when taken in connection with the accompanying drawings, in which

Figure 1 is a vertical sectional view, mostly in elevation, and looking at the back side of a battery for a loom;

Figure 2 is a sectional plan view taken along the line 2—2 in Figure 1;

Figure 3 is a view similar to Figure 1 but showing a modified form of the invention;

Figure 4 is a vertical sectional view taken substantially along the line 4—4 in Figure 1.

Referring more specifically to the drawings, the numeral 10 indicates a portion of a loom frame having a plate or breast beam 11 and also being provided with a lay 13 having a race plate 55

2

14 and a suitable shuttle box on each end thereof, a portion of which is indicated at 15, and into which shuttles 16 may be projected in which position they are disposed during a transfer operation. This loom has a hopper stand 29 secured thereto by one or more screws 21. This hopper stand has a transfer stud 22 fixed therein by any suitable means such as a screw 23, and supports a transfer arm, not shown. The hopper stand 10 has centrally mounted therein a bobbin disk stud 25 which is confined in position by a nut 26. On the bobbin disk stud 25 is mounted for rotation a bobbin disk 27 having a plurality of radially disposed pockets 30 disposed around its periphery 15 in which the butts of bobbins 31 are adapted to be disposed. The hopper stand has extending substantially all the way around its periphery a flange 33 which prevents the bobbins from falling out of the pockets in the bobbin disk except 20 when they have reached transfer position at the lowermost part of the hopper stand, where the projection or rib 33 is not present.

Extending from the periphery of the hopper stand is a projection 35 which has a transverse bore therethrough in which a bobbin support bolt 36 is mounted. This bobbin support is substantially of the structure shown in Patent Number 1,297,420 of March 18, 1919, and comprises a portion 37 for supporting the lowermost bobbin about to be transferred and also has a tail portion 38 which is trough shaped and has portions appearing on both sides of the hopper stand and a transverse bore extends through the portion 38 and is penetrated by the pivot bolt 36 for pivotally supporting the bobbin support.

The bobbin support has integral therewith an arm 40 in which is mounted a bolt 41 which slidably penetrates a projection 42 extending from the rear surface of the hopper stand and a compression spring 44 is disposed between the projection 42 and the headed end of the bolt 41 to apply proper tension to the finger portion 37 which supports the bobbin about to be transferred into the shuttle. The parts thus far described are conventional and it is with a structure of this sort that my invention is adapted to be associated.

During operation of a loom, it very often happens that the projection 35 is broken away as shown in Figure 1 and therefore no means are provided for supporting the bobbin support.

My invention comprises means for supporting this bobbin support pivot bolt so that it is not necessary to install a new hopper stand. My invention also supports the hopper stand from

another portion of the loom to thereby reduce vibration to a minimum when the loom is operated, especially at a high rate of speed.

A loom has an upright and frame member or post 50 on each side thereof which are joined together at their upper ends by an arched portion, not shown. I provide a member, such as a strap iron member 51, and secure one end thereof by means of a bolt 52 to one of the webs of the channelled uprights 50 and another bolt 53 penetrates one leg of an angle bracket 54 as well as the portion 51 to secure the angle bracket to the portion 51 and the other leg of the angle bracket 54 is penetrated by a bolt 56, which penetrates a washer 57 and also penetrates a channel member 50 for rigidly supporting one end of the member 51. The angle member 54 has a downwardly extending leg 59 which is adapted to rest against the post 50 to additionally brace the member 51.

The member 51 has an elongated slot 60 therein which is penetrated by the bolts 52 and 53 to thereby adjust the position of the member 51 with relation to the post 50. The member 51 is bent laterally and downwardly as at 62 and has a horizontally disposed portion 63 having a hole in its right-hand end in Figures 1 and 2 which is penetrated by the bobbin disk stud, and the bobbin disk stud bolt 26 confines that end of member 63 in position.

The form of the invention shown in Figure 3 and which has just been described can be used for bracing the hopper stand of a loom where the projection for supporting the bobbin support has not been broken away. Where this bobbin supporting projection 35 has been broken away, then I may secure by means of bolts 70 the upper end of a member 71 which projects downwardly and then laterally and has an enlarged lower end 73 which is bored to receive the bobbin support bolt 36 to thus support the bobbin support where the supporting projection 35 has been broken away from the hopper stand.

If desired, this member 71 could be employed for additionally supporting the bobbin support bolt 36 even in a hopper stand which did not have the projection 35 broken away from the same and would thus prevent breakage of the projection 35 away from the loom.

It is thus seen that I have provided additional supporting means for the battery hopper stand of a loom and also means associated therewith, if desired, for supporting the bobbin support associated with the battery of the loom.

In the drawings and specification there has been set forth a preferred embodiment of the invention, and although specific terms are employed, they are used in a generic and descriptive

sense only, and not for purposes of limitation, the scope of the invention being defined in the claims.

I claim:

1. In a bobbin changing loom having a frame and a bobbin support and a hopper stand, a supporting device for the bobbin support comprising a bracing member secured at one end to a portion of the loom frame and secured at its other end to a portion of the hopper stand of the loom, said bracing member being provided with a downwardly projecting member having a hole through its lower end adapted to be penetrated by a bolt on which the bobbin support is mounted.

15 2. A loom having a frame, a breast beam, and an uprising member integral with the frame, a battery hopper stand mounted on the breast beam, a bobbin disk stud mounted in said battery hopper stand, a bobbin support which is normally oscillatably mounted in the battery hopper stand, a brace bar secured to the uprising member of the loom at one end and secured on one end of the bobbin disk stud at its other end, an L-shaped member extending downwardly from the brace bar, a bolt extending transversely in the lower end of said L-shaped member and having the bobbin support oscillatably mounted thereon.

20 3. In a loom having a battery comprising a hopper stand and a bobbin disk and a bobbin disk stud and a bobbin support member for supporting a bobbin about to be transferred, and a bolt on which the bobbin support is mounted for pivotal movement, said loom also having an uprising frame member, a brace member, means for securing one end of the brace member to the uprising frame member of the loom, and the other end of the brace member having a hole therethrough adapted to be penetrated by the bobbin disk stud for supporting the hopper stand from the uprising frame member of the loom, the brace member having a downwardly extending arm portion provided with a hole in its lower end adapted to be penetrated by the bolt which supports the bobbin support for thus also supporting the bobbin support of the battery.

45 WILLIAM H. BAHAN.
